UNITED STATES PATENT OFFICE

2,563,058

METAL WINDOW CONSTRUCTION

Harrison Neustadt, New York, N. Y.

Application October 22, 1947, Serial No. 781,310

1 Claim. (Cl. 189—72)

1

The present invention relates to new and useful improvements in window constructions and more particularly to a metal frame and sliding sash.

An important object of the present invention is to provide resilient guide channels for the side edges of the sash and in which the edges of the channels have adjustable friction gripping engagement with the edges of the sash to hold the sash in vertically adjusted position without requiring the use of sash cords or other counter-balancing means for the sash.

Another object of the invention is to construct the sash of spaced parallel panes to provide a dehydrated air space therebetween as an insulating means for the sash without necessitating the use of a storm sash.

A still further object is to provide a novel screen hanger and screen frame construction for use in conjunction with the metal window frame.

A still further object is to provide a device of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view showing the upper and lower sash removed from the window frame;

Figure 2 is an enlarged vertical sectional view through the sash and window frame and also showing the screen in vertical section secured to the outside of the frame;

Figure 3 is an enlarged sectional view taken substantially on the line 3—3 of Figure 1;

Figure 4 is a fragmentary sectional view of the sash frame showing the groove therein for slideable engagement with the channel;

Figure 5 is a fragmentary sectional view taken on a line 5—5 of Figure 1, and;

Figure 6 is a fragmentary transverse sectional view taken on a line 6—6 of Figure 2 and showing the sash lock.

Referring now to the drawings in detail wherein for the purpose of illustration I have disclosed a preferred embodiment of the present invention the numeral 5 designates a metal window frame which includes a metal sill 6 and metal header 7. The head 7 is formed with a stepped portion

2

8 to provide a raised outer portion to receive the upper edge of the upper sliding sash 9.

The upper sliding sash 9 and lower sliding sash 10 are constructed of spaced parallel panes 11 secured in spaced parallel relation to each other and sealed at their edges by a suitable plastic spacing strip 12 to provide a dehydrated air space between the panes. The edges of the panes are cemented or otherwise suitably secured in a channel-shaped sash frame 13 of any suitable metal.

The side edges of the upper and lower sash are slidably received in channel-shaped sash guides 14 of resilient metal construction and secured in vertical position at the sides of the frame 5 by screws 15.

The outer edges of the flanges of the sash guides 14 are bent inwardly in opposed relation with respect to each other to form lips as shown at 16 and are slidably received in vertical grooves

20 17 in the sides of the sash frames 13. The base or web portions 18 of the channels 14 are convexed in a transverse direction to space the longitudinal central portion of the base of the channel-shaped guides 14 from the side of the frame 5 whereby a tightening of the screws 15 will close the inwardly projecting lips 16 of the channel guides toward each other to thus regulate a friction gripping engagement thereof in the grooves 17 of the frame with the sash to thus suitably bind the sash in 25 the guides and hold the sash in a vertically adjusted position in the frame without necessitating the use of sash cords or other counter-balancing means for the sash. The adjusting action of the channels 14 is indicated by dotted lines in

30 35 Figure 3, wherein it will be observed that by pressing the convexed web portion 18 inwardly by the tightening of the screws 15, and since the angle of the flanges 14 relative to the web portion has a tendency to remain constant, the lips 16 of the flanges will be moved toward each other to seat more tightly in the grooves 17 of the sash.

Metal weather stripping 19 is secured to the stepped portion 8 of the header 7 of the window frame for engagement by the upper edge of the upper sash 9 and metal weather stripping 20 is also secured to the sill 6 for engagement by the lower edge of the lower sash 10. The opposed sides at the bottom of the upper sash 9 and at the top of the lower sash 10 are also provided 45 50 with interlocking metal weather stripping 21 of conventional construction.

The sash is locked in a closed position by means of a spring projected bolt 22 slidably carried in the frame 13 at the upper edge of the lower sash 55 and with its outer end arranged for entering an

opening 24 in a block 25 suitably secured to the lower frame of the upper sash 9 as shown in Figure 2 of the drawings.

The lower edge of the upper sash 9 is provided with a handle 26 to facilitate raising and lowering thereof and the lower inner edge of the lower sash 10 is also provided with an angular lift bar 27 suitably secured thereto.

I also provide a screen designated generally at 28 for use in conjunction with the metal window frame 5, the upper edge of the screen being secured between inner and outer rigid metal clamping strips 29 and 30 secured to each other with the screening clamped therebetween by screws or the like 31. The inner strip 29 is of substantially shallow channel-shaped construction and the lower edge of the outer strip 30 is bent inwardly as shown at 32 to enter the channel between the upper and lower flanges 33 and 34 of the strip 29 to effectively bind the screen therebetween.

The outer strip 30 is likewise of substantially shallow channel-shaped construction on which the lower inwardly bent edge 32 forms the lower flange and the upper flange 35 extends upwardly above the inner strip 29 for bearing against the outer surface of the head 7 of the window frame. The strip 30 is formed with one or more openings 36 to receive outwardly projecting hanger hooks 37 welded or otherwise suitably secured to the head 7.

The lower edge of the screen is similarly clamped between inner and outer clamping strips 38 and 39 secured to each other by screws or the like 40, the inner clamping strip having an inwardly projecting flange 41 at its upper edge through which a screw 42 is inserted for threaded engagement in the upper flange 43 of a channel-shaped bracket 44 welded or otherwise secured to the sill 6.

The outer clamping strip 39 is of shallow channel-shaped construction with its lower flange 45 bearing against the outer surface of the sill 6 and its upper flange 46 bearing against the inner strip 38. The strip 39 is also provided with one or more openings 47 for receiving the outwardly projecting hooked lower flange 48 of the bracket 44.

The side edges of the screen 28 are loose to bear against the outer side edges of the frame 5, the screening being held in a stretched position by tightening of the screw 42 in bracket 44.

In view of the foregoing description taken in conjunction with the accompanying drawings it is believed that a clear understanding of the

construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A window construction including a window frame having upper and lower sliding sash therein, each sash including a frame having vertical grooves at its sides, resilient channel shaped guides in the window frame having a pair of parallel flanges and a connecting rib for the flanges, inwardly extended opposed lips on the edges of the flanges engaged in the grooves of the sash, and friction gripping adjusting means for the opposed lips of the guides, said friction gripping adjusting means comprising a longitudinal convexed web portion for the guide, and screws passing through the web portion of the guides and threaded into the window frame to move the opposed lips of the guide relative to each other.
